UNITED STATES PATENT OFFICE.

SADIE LUTTINGER, OF NEW YORK, N. Y.

DESIGN FOR A GARMENT-PROTECTOR FOR NURSING MOTHERS.

45,012.

Specification for Design.

Patented Dec. 9, 1913.

Application filed October 16, 1913. Serial No. 795,573. Term of patent 3½ years.

To all whom it may concern:

Be it known that I, SADIE LUTTINGER, a citizen of the United States, residing at the city of New York, in the county of New York and State of New York, have invented a new, original, and ornamental Design for Garment-Protectors for Nursing Mothers, of which the following is a specification, reference being had to the accompanying drawing, forming part thereof.

Figure 1 is a front elevation of a garment protector for nursing mothers, showing my new design; and Fig. 2 is a rear elevation thereof.

I claim:—

The ornamental design for a garment protector for nursing mothers, as shown.

SADIE LUTTINGER.
